UNITED STATES PATENT OFFICE.

VERNON ROSS, OF KANSAS CITY, MISSOURI.

DISPENSING-MACHINE.

1,218,958.

Specification of Letters Patent. Patented Mar. 13, 1917.

Application filed September 7, 1915. Serial No. 49,200.

To all whom it may concern:

Be it known that I, VERNON Ross, a citizen of the United States, residing at Kansas City, in the county of Jackson and State of Missouri, have invented certain new and useful Improvements in Dispensing-Machines, of which the following is a specification.

This invention relates to dispensing machines of that class for use in the rooms of hotels and other semi-public and public buildings, and the object of the invention is to produce a machine which will operate efficiently and cannot be readily defrauded or get out of order. A further object is to produce a machine which can be easily and quickly charged with articles to be dispensed and which, at a glance, will show whether all or any of its compartments require replenishing.

With these general objects in view the invention consists in certain novel and peculiar features of construction and combinations of parts as hereinafter described and claimed; and in order that it may be fully understood reference is to be had to the accompanying drawings, in which:

Figure 1, is a vertical section taken on the irregular dotted line I—I of Fig. 2, the vending compartment or cylinder in the plane of the section being shown in full lines.

Fig. 2, is a fragmentary front view, partly broken away, and showing one of the series of compartments or cylinders in open position.

Fig. 3, is an enlarged horizontal section on the line III—III of Fig. 1, a certain part or shelf being broken away to disclose underlying features.

Fig. 4, is a fragmentary plan view, part of the casing being shown in section on the line IV—IV of Fig. 1 and certain parts being omitted to more clearly disclose the position and arrangement of certain features.

Fig. 5, is a fragmentary vertical section in the plane of the section of Fig. 1, but showing certain parts in a different position from that which they occupy in Fig. 1.

Fig. 6, is a vertical section of the lower part of one of the dispensing compartments or cylinders.

Fig. 7, is a vertical section taken through the upper end of one of the dispensing compartments or cylinders and a bearing bracket for the upper end of the same.

Fig. 8, is a detail section to show the connection between the shaft actuating spring and a bearing for said shaft.

Referring to the drawings in detail 1 is a wall plate provided with a marginal forwardly projecting bead 2.

3 is a face or cover plate which corresponds in contour to but is smaller than the wall plate, the face plate being open at its rear side and adapted to be fitted against the wall plate and the inner edges of the bead 2, the wall plate thus forming a closure for the open side of the face plate. The face plate is provided with an opening 4 which extends from one end of the plate to the other and from a point near the top of the plate to a point somewhat below the horizontal center of the plate and through this opening access is had for the purpose of charging the machine with the articles to be dispensed or for removing such articles. The means for fastening the face or cover plate in position will be hereinafter described.

Arranged horizontally and fitted against the wall plate near the lower margin thereof is a channel bar, the same comprising a vertically-disposed body 5 and forwardly projecting upper and lower shelves 6 and 7 respectively, the shelf 7 being narrower than shelf 6 and terminating in an upturned flange 8 so that said shelf 7 shall constitute a receptacle for keys or coins employed to unlock the dispensing compartments or cylinders hereinafter described.

9 are screws or bolts extending through the body 5 of the channel bar and through the wall plate into a wall or equivalent support, for the purpose of securing the machine in position. Located in the upper part of the casing constituted by the wall and face plate, is a series of angle brackets 10, and extending through the same and the wall plate and into the wall or its equivalent, are screws or bolts 11, these screws or bolts coöperating with screws or bolts 9 in securing the machine at the desired point.

A series of dispensing compartments or cylinders 12 are arranged between the shelf 6 and the brackets 10, the compartments or cylinders being arranged vertically and close together so that an article cannot be passed between them.

Each compartment or cylinder is provided with an opening 13 through which the loading or unloading of the cylinder is ef-

fected when the same is in open position, as shown by the second cylinder from the right hand end of the machine, in Fig. 2. Each cylinder is provided with a chamber 14 at 5 its lower end and with alined pivots or trunnions 15 and 16 at its lower and upper ends, the same respectively being journaled in shelf 6 and the overlying bracket 10, and to rotate the compartments or cylinders to 10 open position, torsion springs 17 fit around pivots or trunnions 16, and are secured at their opposite ends to their respective cylinders 12 and bearing brackets 10.

Each cylinder is provided with a spring 15 catch for locking it in closed position, that is with its opening 13 facing rearward so as to be inaccessible through the opening 4 of the face plate of the casing. In the preferred construction of the catch mechanism, 20 a short barrel 18 is secured in the chamber 14 of each cylinder, and the catch proper 19 fits vertically in the barrel and normally projects beyond the lower end of the same, being preferably rounded at its lower end. 25 Secured on the catch is a collar 20 to limit its projection from the barrel and afford a shoulder against which the catch projecting spring 21 bears, said spring fitting around the catch and bearing at its opposite 30 end against a fixed part of the cylinder. Normally the spring holds the catch projecting into a locking opening 22 formed in the shelf 6, and intersecting and narrower than said opening is a slot 23 in the shelf. 35 When the catch of a cylinder is repressed to unlocked position as shown in Fig. 5, the spring 17 immediately revolves the cylinder in the direction indicated by the arrow, Fig. 4, from the closed position to open position, 40 that is until pin 24 projecting outward from the lower end of the cylinder strikes and is arrested by a stop pin 25 projecting upward from the shelf, as indicated in connection with one of the cylinders shown in 45 Fig. 4, which cylinder as shown by the corresponding one in Fig. 2, presents its opening 13 to the front.

For each cylinder there is provided a slotted plate 26 through which a coin of proper 50 denomination or its equivalent, such as a key is inserted as a medium through which a particular cylinder shall be unlocked. The plates 26 fit against the outer face of the face plate or cover and are provided with 55 short downwardly and rearwardly extending coin tubes 27 extending through suitable openings in the face plate, the rear ends or extremities of the coin tubes being preferably concaved as shown in Figs. 1 and 5. Each slotted plate 26 is also formed with a rearwardly projecting lug 28 above the tube, and a wedge key or the like 29 extends through the lug to prevent unauthorized withdrawal of the tube.

60 65 30 indicates the face plate of a suitable

lock, the body 31 of which stands within the casing, and is accessible for operation through a key hole 32, and in this connection it will be noted by reference to Fig. 2, that plate 30 is provided with a pair of 70 the coin or key openings like those of plate 26, and that said openings communicate with coin tubes 27 preferably cast integral with plate 30, each of the tubes being associated with one of the rotatable compartments or cylinders 12. The lock is provided with a bolt 33 for upward and downward movement, and the shelf 6 is provided with an opening 34 for the reception 75 of said bolt when the same is in locked position, it being noticed in this connection that when said bolt is withdrawn from engagement with opening 34, the entire cover or face plate, including the lock and the coin tubes, is free to be removed from engagement with the wall plate.

that incidental to this arrest of the shaft through the striking of the shoulders 44 of the arms against said flange will be the positive projection of the coin or key from the pocket of one of said arms into the tray formed by the lower channel bar arm or shelf 7 and the flange 8 thereof, it being understood that this projection of the coin or key occurs after the same has effected the 10 repression of the associated catch 19, as referred to more specifically hereinafter.

To guard against the accidental insertion of a coin or key into the machine while the arms 38 are performing their unlocking operation, a substantially V-shaped guard 45 is arranged below each tube 27, and is pivoted thereto at 46, the free end of the guard being provided with a curved extension 47 which fits flatly against the periphery of 20 the companion arm 38 when the same is in normal position as shown in Fig. 1, and against the lower edge of said arm when the same is in operation to effect the unlocking of the overlying cylinder or is being turned to normal position, it being understood that a suitable spring shown as a torsional spring 48, is mounted on the pivot pin of each of said guards and bears at its opposite ends against a fixed point of the 30 adjacent tube 27 and against said guard for the purpose of raising the same to the position shown by full lines Fig. 5 when not opposed by the spring or springs 42. With the guards thus raised it will be apparent 35 that the accidental insertion of a coin or key cannot result in its loss or in the chocking of the machine as the guard will hold it back until the spring or springs 42 have returned the shaft to normal position. As 40 this occurs the coin or key will drop into the pocket, it being apparent that in the return of the arm to normal position the guards will be swung forward to inoperative position as shown in Fig. 1. It will also be noticed by reference to the last-named figure that there is no danger of a wedging 45 action occurring between the arms and the guards which would interfere with the proper operation of the former by manual 50 manipulation of the handle or head 36, because the curved extensions 47 guard against this contingency.

Assuming a proper coin or key is inserted through one of the slotted plates and drops 55 into the registering pocket, the operator through the instrumentality of the handle or head 36 turns shaft 35 in the direction indicated by the arrow, Fig. 1. In this movement the coin or key is caused to enter and travel rearwardly through the slot 23 in the vertical plane of the pocket containing the coin, and in such passage engages and represses or raises the catch of the overlying cylinder, as indicated in Fig. 5. Before the 60 travel of the coin or key in said slot is com-

pleted, the spring 17 of said cylinder rotates the latter a half revolution, this opening operation of the cylinder immediately following the complete repression or unlocking of the catch. At the same moment the coin 70 or key preferably passes rearwardly of the vertical plane of the axis of shaft 35 and is instantly thereafter ejected from the pocket, the pressure of the catch and the sudden stoppage of the arm due to the striking of 75 the shoulders 44 against flange 8, contributing to make this action positive and quick. The instant the cylinder turns to open position as explained, the operator relaxes the pressure on the handle or head 36, and the 80 spring or springs 42, return the shaft 35 to initial or normal position. All subsequent operations are repetitions of those described.

A suitable key may be used to turn the 85 cylinders back to closed position, the key being inserted through the proper opening 49 in the top of the casing and interlocked with the upper end of the trunnion 16 of the underlying cylinder. 90

As a precaution against robbery of the machines by persons having authorized access to the rooms containing the machines, it is preferable to make at least one side of the slot of each plate 26 of toothed or irregular form as shown at 50, so that a special key or grooved coin or slug will be necessary, these keys or coins being supplied to the guest by the clerk of the hotel who will make a charge for those which have been 100 used. 95

From the above description it will be apparent that I have produced a dispensing machine embodying the features of advantage enumerated as desirable, and while I 105 have illustrated and described the preferred embodiment of the invention it is to be understood that I reserve the right to make such changes in the form, proportion, detail construction and arrangement of the parts 110 as properly fall within the spirit and scope of the appended claims. 115

I claim:

1. In a dispensing machine, a casing, a shelf therein provided with an opening and a slot intersecting the opening, a bearing bracket above the shelf, a compartment standing vertically between and journaled in the shelf and bearing bracket, a spring actuated latch holding the compartment 120 against rotation by engaging the opening in the shelf, an arm provided with an open pocket for receiving and holding a coin so that the same shall project from the pocket, means to turn the arm to cause the projecting portion of the coin to swing through the slot and opening of the pocket to a point beyond the vertical plane of the axis of said arm to successively effect the tripping of the catch 125 and the discharge of the coin from the 130

pocket, and means to turn the compartment the instant the catch tripping operation is completed.

2. In a dispensing machine, a casing, a compartment provided with an opening, within the casing, means for automatically moving the casing to dispose its opening in position where it is accessible, means for normally holding the compartment with its opening inaccessible, a rock shaft journaled in the casing, an arm secured to the rock shaft and provided with a pocket for holding the coin, a coin tube for guiding a coin into said pocket, a handle for turning the shaft and arm to cause the coin to trip the compartment holding means and then effect the discharge of the coin from the pocket, and means to turn the shaft and arm to normal position after the discharge of the coin.
- 20 3. In a dispensing machine, a wall plate, a shelf secured thereto, brackets secured to the wall plate above the shelf, a series of vertical cylinders between and bearing a journaled relation to said shelf and brackets and provided with openings, a face or cover plate fitting against the wall plate and inclosing the parts carried thereby and pro-

vided with an opening, means for locking the face or cover plate to said shelf, means for locking each cylinder with its opening inaccessible through the opening of the face or cover plate, coin-controlled means for tripping the cylinder locking means, and means engaging each cylinder for turning the same when its locking means is tripped, until its opening is accessible through the opening of the face or cover plate.

25 4. In a dispensing machine, a casing, superposed bearings therein, the lower one having a locking opening, a vertical cylinder journaled in the bearings and provided with an opening, a vertically movable catch carried by the cylinder, a spring exerting pressure on the catch to hold the same in engagement with said locking opening, means to effect reversion of the catch from said opening, and a spring to rotate the cylinder about a half revolution the instant the complete reversion of the catch is effected.

45 In testimony whereof, I affix my signature, in the presence of a witness.

VERNON ROSS.

Witness:

50 G. Y. THORPE.
